UNITED STATES PATENT OFFICE

JOHN J. ANDERSON, OF MINNEAPOLIS, MINNESOTA

BOAT PROPELLER

Application filed April 6, 1929. Serial No. 253,102.

This invention relates to boat propellers, and the primary object is to provide a simple, efficient, and practical mechanism for propelling water craft that will utilize a maximum amount of power from the engine or other power unit, that will operate effectively regardless of the shallowness of the water, that will not become clogged by weeds of damaged by rocks, and, by exerting a direct push or action against the water and by submerging in and emerging from the water in substantially vertical directions will not exert wasted energy or meet with unnecessary resistance, as in the case of water wheels now largely employed for this purpose. Further and more specific objects will be disclosed in the course of the following specification, reference being had to the accompanying drawings, wherein:

Fig. 1 is a side elevation of the mechanism showing it as applied to the rear end of a boat, and showing one of the propelling paddles in a position emerging from the water, while the other paddle is in a position ready to be submerged in the water.

Fig. 2 is a plan view of the mechanism shown in Fig. 1, but with fractional portions broken away for purpose of illustration.

Fig. 3 is an enlarged detail view, partly in section, showing the connection between the link bars and the paddle bars.

Fig. 4 is a side elevation similar to Fig. 1, but showing the paddles in advanced positions.

Fig. 5 is a rear view of the propelling mechanism.

Referring to the drawings more particularly and by reference characters, A designates a boat which may be of any size or construction, and upon the rear end of which is secured a frame generally designated by the letter B. This frame comprises a pair of side bars 6 and 7, connected at their rear ends by a cross bar 8. At its front end the frame bars 6 and 7 are connected by a cross bar 9, and at intermediate points the side bars are connected by a cross bar 10 which in turn is braced by a pair of braces 11, secured at their outer ends adjacent the rear ends of the bars 6 and 7. Upon the front end

of the frame B is secured a pair of laterally disposed standards 12 which rigidly support a cross bar 13 having lug projections 14 at its ends. These lugs 14 serve as bearings for a shaft 15 having cranks 16 and 17 at its outer ends. These cranks, in the present instance, are provided with pitman bars 18 which transmit power to the shaft 15 from the engine or power unit (not shown) of the boat, in the usual manner, but it is to be understood that any desired mechanism may be employed for rotating the shaft 15. The outer ends of the cranks 16 and 17 are connected by link bars 19 and 20, the lower rear ends of which are pivotally connected to blocks 21, each of which is slidably mounted on a pair of parallel race bars 22. Each set of race bars 22 is anchored at its forward end in a depending bracket 23 at the end of the bar 10, and the rear ends of the race bars 22 are anchored in posts 24 extending downwardly from the rear end of the frame B. Thus, the two sets of race bars 22 are firmly held in inclined, parallel and rigid conditions.

Journalized in the blocks 21 are a pair of crank bars 25 which are provided at their rear ends with rigid transversely disposed paddles 26 and 27. The forward or crank ends of the bars 25 are journalized in sleeves 28 (see Fig. 3) carried by the blocks 21, but at their outer ends these cranks are non-rotatably secured to the rear ends of the link bars 18 and 19. Thus, when the link bars 18 or 19 successively move upward and downward the paddles 26 and 27 will be successively moved downward and upward, and as the link bars move forward over the center of the shaft 15 they will operate the paddles 26 and 27 downwardly and rearwardly, with a result that the paddles will move rearwardly only when they are substantially below the water level, and as soon as they successively reach their rearmost positions they will be lifted and returned to their foremost positions in a substantially horizontal path above the water level.

The inclined positions of the race bars 22 are so associated with respect to the power shaft 15 that they will further serve to give

the paddles 26 and 27 the proper operating action when in use.

From the foregoing description it will be obvious that by reversing the direction of rotation of the shaft 15 the paddles 26 and 27 will operate to pull the boat rearwardly through the water.

It is understood that suitable modifications may be made in the structure as disclosed, provided such modifications come within the spirit and scope of the appended claims.

Having now therefore fully illustrated and described my invention, what I claim to be new and desire to protect by Letters Patent is:

1. A boat propelling mechanism comprising a pair of laterally disposed races, blocks slidably carried by and on the races, a pair

20 of paddles having shafts pivotally carried by the blocks, a pair of link bars attached to the paddle bars and for reciprocating the race blocks, each of said paddle shafts being relatively rigid with respect to one of the link bars.

25 2. A boat propelling mechanism comprising a pair of laterally disposed races, blocks slidably carried by and on the races, a pair of paddles having shafts pivotally carried by the blocks, a pair of link bars rigidly connected to the respective paddle bars and for reciprocating the race blocks, and a pair of crank arms for actuating the link bars.

30 3. A boat propelling mechanism comprising a pair of laterally disposed races, blocks slidably carried by and on the races, a pair of paddles having shafts pivotally carried by the blocks, a pair of link bars rigidly connected to the respective paddle bars and for reciprocating the race blocks, a rotatable power shaft and cranks on said shaft connected with the link bars for actuating the latter.

35 4. A boat propelling mechanism comprising a frame carried rearwardly of the boat and having a pair of laterally disposed parallel races, a pair of transversely disposed paddles each pivotally and slidably associated with one of the races, and continuously operative means for actuating the paddles with respect to the races whereby they will successively move in an elliptical course rearwardly in a relatively low course and forwardly in a relatively high course.

40 5. A boat propelling mechanism comprising a frame carried rearwardly of the boat and having a pair of laterally disposed inclined races, travellers carried by the races for alternate reciprocating movements thereon, paddles pivotally carried by the travellers, and means for alternately reciprocating the travellers and successively raising and lowering the paddles.

45 6. A boat propelling mechanism comprising a frame carried rearwardly of the boat and having a pair of laterally disposed inclined races, travellers carried by the races for al-

ternate reciprocating movements thereon, paddles pivotally carried by the travellers, and means for alternately reciprocating the travellers and successively raising and lowering the paddles, said last mentioned means including a crank shaft and link connections extending therefrom to the travellers and paddle members.

7. A boat propelling mechanism comprising a frame carried rearwardly of the boat and having a pair of laterally disposed inclined races, travellers carried by the races for alternate reciprocating movements thereon, a pair of transversely disposed paddles each carried by a bar pivotally associated with one of the travellers, and means rigidly connected with the respective paddle bars for simultaneously reciprocating the travellers and oscillating the paddle bars.

8. A boat propelling mechanism comprising a frame carried rearwardly of the boat and having a pair of laterally disposed inclined races, travellers carried by the races for alternate reciprocating movements thereon, a pair of transversely disposed paddles each carried by a bar pivotally associated with one of the travellers, a pair of link bars rigidly connected to the paddle bars, and rotatable means for actuating the link bars.

9. A boat propelling mechanism comprising a frame carried rearwardly of the boat and having a pair of laterally disposed races, travellers carried by the races for reciprocating movements thereon, a pair of transversely disposed paddles having crank arms pivotally secured to and carried by the travellers, a crank shaft journaled rearwardly in the frame, and link bars secured at their fore ends to the cranks of the crank shaft, and rigidly secured at their rear ends to the paddle crank arms for actuating the latter.

Signed at Minneapolis, in the county of Hennepin and State of Minnesota, this 4th day of April 1929.

JOHN J. ANDERSON.
